UNITED STATES PATENT OFFICE.

GLADYS FANNIE MALLORY, OF MARTINS FERRY, OHIO.

COMBINED WINDOW SHADE AND DRAPERY SUPPORT.

Application filed March 6, 1926. Serial No. 92,918.

- This invention relates to a combined shade and drapery support, and it has for its primary object to provide a support or hanger for window shades and draperies which 5 may be readily swung to a position in which is afforded convenient access to the window, as for washing, without either removing such shades and draperies from said support or in any way disarranging the same.
- 10 A further object is to provide a device of the character mentioned which is inexpensive to manufacture, which is readily adjustable to fit windows of different widths, and which may be readily shifted to and 15 from its normal position without ascending a step ladder or other elevated support.
- In describing the invention in detail, reference is herein had to the accompanying drawings, in which—
- 20 Figure 1 is a front elevation of the invention, showing it in its normal position on a window casing.
- Figure 2 is a top plan view of the same;
- Figure 3 is an enlarged end elevation of 25 the same;
- Figure 4 is an enlarged detail section of the shiftable member, showing the drapery rod supports, said section being taken on line 4—4, Fig. 1; and
- 30 Figure 5 is an enlarged section on line 5—5, Fig. 2.
- Referring to said drawings, 1 and 2 indicate two relatively shiftable sheet metal sections which complementally form a bar-like 35 member A adapted to be mounted stationarily, as by means of screws 3, upon the face of the horizontal cap member 4 of a window casing.
- The outer end of the section 2 has pivot- 40 ally attached thereto one of two relatively adjustable sections 5 and 6 which complementally form a bar-like member B which is shiftable relative to the stationary member above described, said sections 2 and 6 45 preferably having their adjacent ends shaped to form complementary members of a hinge having a connecting pintle 7. Said sections 5 and 6 have in their meeting end portions corresponding longitudinal slots 8 through 50 which are directed connecting screws or bolts 9 which may be adjusted to secure said sections in relatively adjusted position to provide the length of member required. Similarly, screws or bolts 10 connect the relatively adjustable sections 1 and 2 of the 55 stationary member A of the support.

Carried by the shiftable or hinged bar B adjacent to the opposite ends of the latter are shade supporting brackets 11 and 12 adapted for the reception of the usual pins 60 carried by the opposite ends of shade rollers, said brackets being preferably formed integral with and depending from the lower edge of said bar, as shown.

A plurality of hooks 13 for the support of 65 telescoping drapery supporting rods 14 of an ordinary commercial type are mounted in the shiftable or hinged member B adjacent to its opposite ends.

The outer end of the section 5 of the 70 hinged member B has a tongue-like extension 15 which, in the normal position of said member, overlies a projecting lug 16 formed on or carried by the corresponding end of the bar A, thereby to provide for rigidly 75 supporting the said end of the bar B. A rod 17 attached to and depending from said tongue 15 may be employed for lifting the end of the bar B out of and into supported relation to said lug 16, thereby to avoid 80 the necessity for ascending a step ladder or other elevation to engage and disengage the tongue with respect to the lug.

As a means for preventing sagging of the 85 hinged member B under the weight imposed thereon by the shade and the draperies when said member is swung outward to a position affording access to the window, a supporting brace 18 is provided. Said brace, composed of telescoping members, has one 90 end pivotally mounted in a supporting member 19 fixed at a suitable point on the window casing and inclines thence upward and has its opposite end attached to a lug 20 formed on the section 5 of the member B. 95

From the foregoing description it will be seen that the invention provides a simple, inexpensive and convenient form of shade and curtain support which may readily be swung to and from its normal supporting 100 position with relation to a window. Further, it will be manifest that various changes in the forms and arrangement of some of the parts may be resorted to without departing from the spirit or scope of the invention as 105 defined in the appended claim.

What is claimed is—

A holder for shade and drapery fixtures, comprising a sectional bar for mounting stationarily upon a window casing, said bar 110 having a hinge member formed at one end thereof and carrying an outstanding lug at

its opposite end, a sectional bar adapted for outward swinging movement relative to the first mentioned bar and having at one end thereof a hinge member complementary to that of said first bar and connected to the latter, the last mentioned bar having a portion adapted to rest normally upon said lug, curtain-rod and shade-roller supports carried by said second bar, means connected to and depending from said second bar whereby

the latter may be elevated by hand into and out of supported relation to said lug, and a pivoted supporting brace having connection with said second bar and upon which the latter is supported in its outwardly swung ¹⁵ position.

In testimony whereof, I affix my signature.

GLADYS FANNIE MALLORY.
